CLAIM

The ornamental design for a space-saving travel bottle, substantially as shown and described.

DESCRIPTION

FIG. 1 is a front perspective view of an embodiment of a space-saving travel bottle in accordance with our new design;

FIG. 2 is a front view of the embodiment thereof;

FIG. 3 is a back view of the embodiment thereof;

FIG. 4 is a right side view of the embodiment thereof;

FIG. 5 is a left side view of the embodiment thereof;

FIG. 6 is a top view of the embodiment thereof; and,

FIG. 7 is a bottom view of the embodiment thereof.

The broken lines of the Figures are for illustrating portions of the space-saving travel bottle that form no part of the claimed design.
